UNITED STATES PATENT OFFICE

HILDUR S. MOORE, OF ST. PAUL, MINNESOTA

DESIGN FOR A CANDY DOLL

Application filed September 19, 1928. Serial No. 28,198. Term of patent 3½ years.

To all whom it may concern:

Be it known that I, HILDUR S. MOORE, a citizen of the United States, residing at St. Paul, county of Ramsey, and State of Minnesota, have invented a new, original, and ornamental Design for Candy Dolls, of which the following is a specification, reference being had to the accompanying drawing, forming part thereof.

The figure is a perspective view of a candy doll constituting the design.

I claim:

The ornamental design for a candy doll, as shown.

HILDUR S. MOORE.
